SPRING GROUP

Robert B. Cottrell, Chicago, Ill., assignor to
American Steel Foundries, Chicago, Ill., a cor-
poration of New Jersey

Application November 21, 1941, Serial No. 419,881

20 Claims.

(Cl. 267—9)

My invention relates to a spring group comprising a control unit and particularly adapted for use on railway equipment but suitable for any application where it is desired to restrain normal oscillatory action of coil springs or similar devices.

In recent years considerable effort and study has been directed to the solution of problems arising from the uncontrolled actions of coil springs when used on vehicles, particularly railway equipment. At the present time, it is well recognized that some sort of snubbing means is desirably used in association with coil springs and sometimes elliptic springs as well, although when properly designed, an elliptic spring has qualities of friction absorption which may prevent the development of synchronous vibrations. To those skilled in the art, it will be apparent that in the modification shown herein, by means of parallel friction surfaces, uniform pressure and friction is obtained throughout the stroke or spring travel.

A more specific object of my invention is to design a snubbing arrangement comprising a top follower or housing having flat vertical friction walls, said arrangement also comprising shoe carriers or support means upon which friction shoes may be mounted for frictional engagement with the inner surfaces of said walls.

Another object of my invention is to provide a friction control unit comprising, in one modification, adjustably mounted friction shoes and in other modifications adjustably and removably mounted friction shoes.

My invention comprehends a novel form of bottom follower or friction shoe support comprising in certain modifications horizontal flanges extended through aligned slots in the associated shoes and in another modification comprising slots formed for the reception of securing lugs on the associated shoes.

My invention also contemplates such an arrangement as that described wherein adequate friction may be developed by a device comprising relatively few parts and a relatively thick rubber spring or pad.

Figure 1 is a top plan view of one modification of my novel control unit with the top spring plate shown in phantom lines in order to show more clearly the structure therebeneath.

Figure 2 is an end view of the structure shown in Figure 1 partly in section, the section being taken in the vertical transverse plane indicated by line 2—2 of Figure 1.

Figures 3 and 4 show my novel form of locking link engaged with the associated top fol-

lower, Figure 3 being a plan view thereof and Figure 4 an end view.

Figures 5 and 6 show my novel friction device in conjunction with a coil spring group, Figure 5 being a top plan view with the top spring plate partly broken away to show the friction device therebeneath, and Figure 6 being an end view thereof corresponding to the view shown in Figure 2.

Figures 7 and 8 show another modification of my novel unit, Figure 7 being a top plan view thereof, and Figure 8 an end view.

Figures 9, 10, and 11 show the modified friction shoe retainer used in the arrangement shown in Figures 7 and 8, Figure 9 being a plan view thereof, Figure 10 a side elevation, and Figure 11 an end view.

Figure 12 shows still another modification of my novel ride control unit and is a sectional view taken in a vertical transverse plane bisecting one pair of the friction shoes employed in my unit, said view being comparable to that shown in Figure 2 but showing both sides of the unit in section.

25 Describing my novel control unit in detail and referring particularly to the assembly view shown in Figures 1 and 2, the control unit comprises a housing or top follower 2 of generally rectangular box-like form having side walls 4, 4, end walls 6, 6, a top wall 8 integrally formed there-

30 with, and slotted as at 9, 9, and an intermediate transverse vertical web 14 relieved as at 15 (Figure 2) for the purpose of lightening the device. The top wall 8 may be projected centrally of the device to form the lateral retaining lugs 10,

35 10 and said lugs on said top wall may be perforated as at 12, 12 for reception of rivets or similar securing means by which the top follower or housing may be fixed to a top spring plate or other spring abutting means. Each

40 side wall 4 is formed with spaced slots 16, 16 at the bottom thereof and intermediate its junction with the transverse web 14 and the end walls 6, 6, thus affording clearance on the closure stroke for the top follower from the shoe retainers 17, 17 and the members 24, 24 securing said

45 retainers to the bottom spring plate. On the inside of the side walls 4, 4 are formed friction surfaces 26, 26 (Figure 2) for engagement with abutting surfaces 28, 28 on the friction shoes 27, 27 hereinafter described in greater detail.

50 The end walls of the top follower may be projected adjacent the bottoms thereof to form the hook-like lugs 13, 13 serving a purpose hereinafter described.

55 Vertically aligned with the slots 16, 16 at

each end of the device is a shoe retainer 17 of strap-like form and comprising a base portion 18 perforated as at 19 for reception of securing means 20 by which it may be fixed to a bottom spring plate 41. At the sides of the base portion 18 are formed upwardly curved vertical portions 21, 21 which are extended into horizontal flanges 22, 22 serving as friction shoe supporting means in the manner hereinafter described.

Secured to the ends of said horizontal flanges as at 23, 23 by welding or other convenient means are vertical lugs 24, 24 of rectangular form which are in turn fixed to the bottom spring plate as at 25, 25 and thus furnish support for said shoe retainers 17, 17.

Each shoe 27 is of generally rectangular form comprising an upper relatively thick portion 29 on one side of which is formed a friction surface 28 for engagement with the adjacent friction surface 26 on the top follower 2 as heretofore described, and on the other side of said thick portion is formed a centrally disposed annular lug 30 which affords positioning means for a rubber pad or spring 39 normally under compression between said shoes 27, 27 at each end of the device. The lower relatively thin portion 33 of each shoe is formed with a rectangular slot 34 adjacent the bottom thereof for reception of a horizontal flange 22 on the associated shoe retainer 17, thereby positioning said shoe 27 and limiting movement thereof with respect to said bottom spring plate. It may be noted that the flanges 22, 22 are afforded slight play within the slots 34, 34 in the associated shoes so that said shoes may automatically adjust themselves in the event of wearing of the surfaces 26, 26 and 28, 28.

At each end of the device a retaining link 35 may be fixed to the bottom spring plate as by welding at 36, 36. Said link is shown in detail in Figures 3 and 4 and comprises a base portion 37 welded to the bottom spring plate as above described and an arcuate upper portion 38 engaged with the hook-like lug 13 on the adjacent end wall 6 of the top follower 2. Said link may be used in assembly of my novel unit, and after the device has been placed under load the link may be removed if desired.

Figures 5 and 6 show in reduced size the application of my novel control unit to a spring group. Said spring group comprises the top spring plate 40 and the bottom spring plate 41, said top plate being flanged over its outer edge in an arcuate or scallop-like arrangement as at 42 to serve as positioning means for spaced coil springs 43, 43 (diagrammatically indicated), and said bottom plate comprising spaced openings 51, 51 for association with positioning lugs on a bottom frame member (not shown). The inboard edge 44 of the plate 40 is plain and unflanged and by this means interference is avoided with a commonly used form of load carrying member or bolster (not shown) normally supported thereon. The bottom plate 41 is upwardly flanged at its outboard end as at 45 and at its inboard end as at 46, thus affording positioning means for the coil springs at each end of the group. Secured to the top and bottom spring plates as at 47, 47 may be my novel control unit generally designated 48 of a form heretofore described in detail, including the top follower 2 and the shoe retainer 17, secured respectively to the top and bottom spring plates. The spring plates may be formed with central lugs 49, 49 serving as positioning means for said plates with

respect to the supporting and supported frame members (not shown). It may be noted that the contour of the securing lugs 10, 10 on the top follower 2 may be such as conveniently to form additional positioning means for the coil springs as at 50, 50.

It will be understood that in assembling my novel device, the shoes may be clamped together with the rubber springs under compression therebetween after which the housing may be placed in position thereover, and thereafter the retaining ring 35 and the securing members 24, 24 associated with the shoe retainers 17, 17 may be positioned and welded as before described. As the clamp is released from the shoes they will be forced against the opposite friction surfaces of the housing thus developing the desired friction. It will be apparent that the character of the rubber pads or springs may be varied to meet different operating conditions.

In Figures 7 to 11 another modification of my device is shown, and in this modification the top follower or housing 52 comprises side walls 54, 54, end walls 56, 56, a top wall 58 integrally formed therewith and slotted as at 55, 55, and an intermediate vertical transverse web 59 cored away as at 60 (Figure 8) at the bottom thereof and thus affording clearance for the shoe retainer 69 on the closure stroke. The top wall 58 may be projected to form lateral retaining lugs 61, 61 with perforations 62, 62 and serving a purpose similar to that of the corresponding lugs in the previous modification. The side walls 54, 54 are formed with friction surfaces 63, 63 for engagement with abutting surfaces 64, 64 on the friction shoes 65, 65 as at 66, 66, and the end walls of the housing may be projected to form hook-like lugs 67, 67 engaging the assembling links 68, 68 as in the previous modification.

The shoe retainer 69 shown in detail in Figures 9 to 11 is an E-shaped member comprising relatively narrow end legs 70, 70, a relatively wide intermediate leg 71, and a rectangular top wall 72. Between the legs 70, 70 and the leg 71 are formed spaced slots 73, 73 for reception of horizontal lugs 88, 88 on the bottom of the associated friction shoes 65, 65. The bottom follower may be secured to the bottom spring plate by welding or other convenient means as at 75, 75.

The friction shoes 65, 65 are similar to those described in the previous modification and comprise upper relatively thick rectangular portions 78, 78, having on one side thereof friction surfaces 64, 64 engaging complementary surfaces on the side walls of the housing as previously described and on the other side thereof centrally positioned annular lugs 80, 80 forming positioning means for rubber pads or springs 84, 84 normally under compression between the shoes at respective ends of the housing 52. The lower relatively thin portions 86, 86 of the shoes comprise horizontal lugs 88, 88 at the bottom thereof extending into the slots 73, 73 in the bottom follower 69 thus limiting relative vertical movement between the shoes and the bottom spring plate while permitting lateral movement of said shoes in order that they may adjust themselves to wearing of the surfaces 63, 63 and 64, 64 on the top follower and shoes respectively. At each end of the device, a retaining link 68 may be secured to the bottom plate and may engage a lug 67 on the top follower 52 as previously described and for assembly purposes as described in the previous modification.

In the modification shown in Figure 12, the ride

control unit is similar to those modifications heretofore described and comprises top and bottom spring plates 102 and 104 of similar form to those employed in the previous modifications and comprising lugs 106, 106 affording means positioning said plates with respect to the supported and supporting frame members (not shown). The unit also comprises a top follower generally designated 108 secured as at 110, 110 to said top spring plate and comprising side walls 112, 112 presenting oppositely spaced friction surfaces 114, 114 relieved as at 116, 116. At each end of the device is positioned a pair of friction shoes 118, 118 with wear pads 120, 120 secured thereto in any convenient manner and in frictional engagement as at 122, 122 with the friction surfaces 114, 114 on the top follower. Each shoe 118 comprises a pair of vertically aligned lugs 124, 124 serving a purpose hereinafter described, and each shoe also comprises an offset base portion 126 with an opening 128 therethrough for the reception of positioning means formed on the bottom spring plate 104. Said positioning means comprises a shoe retainer of T-section comprising a vertical web 130 integrally formed with the bottom plate and a horizontal web 132, each side of which projects through the opening 128 in the associated friction shoe. Under compression between each pair of friction shoes 118, 118 is a pair of vertically aligned coil springs 134, 134, said springs being positioned with respect to said shoes by the lugs 124, 124 formed thereon as previously described. It will be noted that in the modification shown in Figure 12, the shoes are offset at the lower extremities thereof in order that they and the shoe retainer associated therewith may be afforded clearance from the top follower on the closure stroke. It may also be noted that in this modification as well as in the modification shown in Figures 7 to 11 inclusive, the friction shoes are removably secured with respect to the bottom spring plate and are permitted lateral movement with respect to the associated shoe retainer in order that they may adjust themselves to wearing of the friction surfaces on the top housing and on said shoes.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a composite spring group for a railway car truck, top and bottom spring plates, a plurality of coil springs confined therebetween, and a friction device, said device comprising a top follower secured to said top plate and having spaced friction surfaces, friction shoes in engagement with respective surfaces and comprising slots therethrough, resilient means under compression between respective shoes, a plurality of shoe retainers fixed to said bottom plate and comprising horizontal flanges in engagement with respective slots, an outwardly extending lug at each end of said top follower, and an assembly link at each end of said device comprising a horizontal base portion fixed to said bottom plate, and an arcuate upper portion engaged with said lug.

2. In a composite spring group for a railway car truck, top and bottom spring plates, a plurality of coil springs confined therebetween, and a friction device, said device comprising a top

housing secured to said top plate and having oppositely spaced friction surfaces, friction shoes therein in engagement with respective surfaces and comprising slots therethrough, and a plurality of shoe retainers secured to said bottom plate and comprising horizontal flanges extending through respective slots, resilient means under compression between respective shoes, and means securing said horizontal flanges to said bottom plate.

3. In a spring group for a railway car truck, top and bottom spring plates, a plurality of coil springs confined therebetween, and a friction device, said device comprising a housing secured to said top plate and having oppositely spaced friction surfaces at each end thereof, a friction shoe in engagement with each surface and comprising a rectangular slot, a shoe retainer secured to said bottom plate at each end of said device and comprising horizontal flanges extending through respective slots in said shoes, and resilient means under compression between said shoes at each end of said device.

4. In a composite spring group for a railway car truck, top and bottom spring plates, a plurality of coil springs confined therebetween, a rectangular housing fixed to said top plate and comprising oppositely spaced friction surfaces, a plurality of friction shoes therein engaging respective surfaces and comprising slots therethrough, a plurality of shoe retainers, each comprising a horizontal base portion secured to said bottom plate, and spaced horizontal flanges extending through respective slots, and rubber pads under compression between respective shoes urging said shoes into engagement with said surfaces.

5. In a composite spring group for a railway car truck, top and bottom spring plates, a plurality of coil springs confined therebetween, and a friction device, said device comprising a top follower having side walls comprising internal friction surfaces and end walls each comprising an outwardly extending lug, friction shoes in engagement with said surfaces, shoe retaining means associated with said bottom plate and engaged with said shoes, resilient means urging said shoes into engagement with said surfaces, and an assembly link at each end of said device secured to said bottom plate and having an upper portion engaged with the adjacent lug.

6. In a composite spring group, top and bottom spring plates, a plurality of coil springs confined therebetween, and a friction device, said device comprising an E-shaped shoe retainer having spaced legs fixed to said bottom plate, a rectangular housing secured to said top plate and having oppositely spaced friction surfaces, friction shoes in engagement with respective surfaces and comprising horizontal lugs extending between respective legs on said shoe retainer, and resilient means under compression between respective shoes.

7. In a composite spring group for a railway car truck, top and bottom spring plates, a plurality of coil springs confined therebetween, and a friction device, said device comprising a housing secured to said top plate having side walls comprising internal friction surfaces and end walls each comprising an outwardly extending lug, friction shoes in engagement with said surfaces, means adjustably securing said shoes to said bottom plate, resilient means urging said shoes into engagement with said surfaces, and links fixed to said bottom plate at the

ends of said device and looped over said lugs to limit expansion of the device.

8. In a composite spring group for a railway car truck, top and bottom spring plates, a plurality of coil springs confined therebetween, and a friction device, said device comprising a housing secured to said top plate and having oppositely spaced friction surfaces therein and a vertical transverse web bisecting said surfaces, friction shoes in engagement with said surfaces, shoe retaining means secured to said bottom plate and removably engaged with said shoes, resilient means urging said shoes into engagement with said surfaces and a slot in said web affording said top housing clearance from said shoe retaining means.

9. In a friction absorbing device, a housing having a pair of opposed internal friction faces at each end thereof, friction shoes engaging respective faces, resilient means for urging said shoes into said engagement, follower means interlocked with said shoes, and resilient means reacting against spring abutment means fixed to said housing and said follower means respectively.

10. In a friction device, a top housing comprising oppositely spaced friction surfaces, and an integral transverse vertical web bisecting said surfaces, friction shoes in engagement therewith, each having a rectangular slot through the base thereof, a plurality of shoe retainers having securing portions extending through respective slots, and rubber pads under compression between respective shoes.

11. In a friction device, a top housing comprising a pair of oppositely spaced friction surfaces at each end thereof, sets of friction shoes in engagement with respective surfaces, shoe retaining means securing the friction shoes at each end of the device, and resilient means under compression between the shoes at each end of the device, said friction surfaces having spaced slots affording clearance from said shoe retaining means.

12. In a friction absorbing device, a housing having internal friction surfaces, a pair of opposed friction shoes at each end of said housing in frictional engagement with the associated surfaces, resilient means urging said shoes into said engagement, follower means interlocked with said shoes, and resilient means reacting against abutment means fixed to said follower means and housing respectively.

13. In a composite spring group, top and bottom spring plates, a coil spring confined therebetween, and a friction device, said device comprising a housing secured to said top plate and having a pair of oppositely spaced internal friction surfaces at each end thereof, friction shoes in frictional engagement with respective surfaces and adjustably secured to said bottom plate, and resilient means under compression between said shoes and urging said shoes into engagement with said surfaces.

14. In a friction absorbing device, a housing having internal friction surfaces, a pair of opposed friction shoes at each end of said housing in engagement with the associated surfaces, resilient means compressed between each pair of shoes

for urging the same into engagement with said surfaces, follower means interlocked with said shoes, and resilient means reacting against abutment means fixed to said follower means and housing respectively.

5 15. In a friction device, a top follower having spaced friction panels, an E-shaped shoe retainer comprising spaced legs, friction shoes having bottom portions extending between respective legs and friction surfaces in engagement with respective panels, and resilient means under compression between respective shoes.

10 16. In a friction absorbing device, a housing having side walls comprising internal friction surfaces and end walls each comprising an external lug, friction shoes in engagement with said surfaces, follower means interlocked with said shoes, resilient means urging said shoes into engagement with said surfaces, spaced spring abutment means fixed to said housing and said follower means respectively, resilient means reacting against said spaced abutment means, and links fixed with respect to said follower means and looped over respective lugs to limit expansion of the device.

15 17. In a friction absorbing device, a housing follower having spaced side walls, a top wall, and a transverse web integral with said top and side walls and substantially bisecting said side walls, friction shoes frictionally engaging the inner surfaces of said side walls at opposite sides of said web, resilient means urging said shoes into said engagement, a follower interlocked with said shoes, and a plurality of spaced slots extending through said top wall, each of said slots being disposed substantially in vertical alignment with one of said shoes.

20 18. In a friction device, a follower having spaced friction panels, an E-shaped shoe retainer comprising spaced legs, friction shoes having portions extending between respective legs, said shoes comprising friction surfaces in engagement with respective panels, and resilient means for urging said surfaces into said engagement.

25 19. In a spring group, top and bottom spring plate members, a coil spring therebetween, a housing secured to one of said members and having a pair of oppositely spaced internal friction faces at each end thereof, pairs of shoes in frictional engagement with respective faces, resilient means urging said shoes into said engagement, and an E-shaped follower secured to the other member and having a plurality of substantially parallel legs defining slots therebetween for the reception of lugs on the adjacent ends of said shoes.

30 20. In a composite spring group, top and bottom spring plates, a spring extending therebetween, and a friction device comprising a housing secured to one of said plates and having a pair of oppositely spaced internal friction surfaces at each end thereof, friction shoes in frictional engagement with respective surfaces and adjustably secured to the other of said plates, and resilient means under compression between said shoes for urging the same into engagement with said surfaces.

ROBERT B. COTTRELL.
